UNITED STATES PATENT OFFICE.

AVERY BRADLAUGH NEWSON, OF SALT LAKE CITY, UTAH.

SWING.

Application filed June 25, 1926. Serial No. 118,557.

My invention relates to improvements in swings, and it consists in the combinations, constructions and arrangements herein described and claimed.

5 An object of the invention is the provision of a swing which is adapted to be actuated by bodily movements of a user or users of the swing and which cannot be overturned accidentally in use and therefore is absolute-
10 ly safe for the use of children.

A further object of the invention is the provision of a swing of the character described which can be made almost entirely of lengths of pipe and pipe fittings, and which can be made to accommodate one or more users.

A still further object of the invention is the provision of a swing which is easy to operate, strong and durable, not likely to get out of order easily and thoroughly practical commercially.

Other objects and advantages of the invention will be apparent from the following description, considered in conjunction with the accompanying drawings, in which

Figure 1 is a perspective view of a swing embodying the invention as it appears in a position of rest,

Figure 2 is a side elevation of the improved swing, showing in full lines the swing in its position of rest, and showing in dotted lines two different positions of the swingable frame structure of the device during the operation of the swing, portions of the supporting structure of the device being broken away.

Figure 3 is a transverse vertical section through the swing substantially along the line 3-3 of Figure 2,

40. Figure 4 is a relatively enlarged section substantially along the line 4-4 of Figure 3,

Figure 5 is a relatively enlarged fragmentary sectional view substantially along the line 5-5 of Figure 2.

The supporting structure of the swing includes a substantially rectangular base frame which comprises a pair of parallel side members 1, which preferably are lengths of pipe, a pair of parallel end members 2 which also preferably are lengths of pipe and suitable pipe fittings, such as the street elbows 3 and the T's 4, which connect adjacent ends of the side members 1 and the end members 2. The street elbows 3 are attached directly to the end members 2 and the T's 4

are arranged to connect the street elbows 3 with the side members 1 and are adjusted so that branches 5 of the T's are turned upward. Standards 6, which also may be lengths of pipe are connected with the upturned branches 5 of the T's 4, as by means of cooperative internal screw threads on the branches 5 and external screw threads on the lower end portions of the standards 6, whereby the standards 6 will be supported in vertical positions and the standards 6 at each of the opposite ends of the base frame will be in alignment transversely of the frame. The standards 6 are stayed to the side members 1 of the base frame by brace bars 7 and are stayed to the end members 2 of the base frame by brace bars 8. The base frame may be supported in horizontal position slightly above the earth's surface in any suitable manner, as by means of a pair of spaced transverse supporting blocks or ties 9 on which the side members 1 of the base frame rests adjacent to opposite ends of the base frame and through which the side members of the base frame may be secured by fastening devices 10. The swingable structure of the device includes pairs of hanger bars 11 at opposite ends of the stationary frame structure, the respective hanger bars 11 of each pair being connected with each other at their lower ends by a shaft 12 and being supported at their upper ends on the extending adjacent end portions of axially aligned short shafts 13 which are carried by the upper end portions of the standards 6 at the corresponding end of the stationary frame structure. The short shafts 13 may be rods projected through diametrically opposite openings in the walls of the associated standards 6 as shown to advantage in Figure 5 and retained in place by nuts 14 and washers 15 on the outer end portions of the shafts 13 and fixed collars 16 on the shafts 13 in abutting relation to the inner side portions of the standards 6. The upper end portions of the hanger rods 11 preferably are flattened as indicated at 17 and are provided with transverse openings, as indicated at 18 for the reception of the inner end portions of the shafts 13, the walls of the openings 18 being formed with counterbores 19 and 20 respectively, the counterbores 19 being adapted to partially receive the fixed collars 16 and the counterbores 20 being adapted to partially receive collars, as at 21, which are in threaded en-

gagement with the inner end portions of the shafts 13, the adjacent portions of the collars 16 and walls of the counterbores 19 and the adjacent portions of the collars 21 and the walls of the counterbores 20 being cooperatively formed to produce race-ways for ball bearings 22. Lock nuts 23 are in threaded engagement with the extreme inner end portions of the shafts 13 to prevent accidental displacement of the parts which constitute the anti-friction assemblies on the inner end portions of the shafts 13. The lower end portions of the hangers 11 also preferably are flattened at 24 and as clearly shown in Figure 4, are provided with transverse openings 25 adapted to loosely receive the end portions of the shafts 12. The walls of the openings 24 are enlarged at their opposite ends to partially receive collars 26 and 27 respectively on the end portions of the shafts 12, the adjacent portions of the walls of the openings 25 and the collars 26 and 27 being cooperatively formed to provide race ways for ball bearings 28. The collars 26 abut shoulders 29 on the shafts 12 and nuts 30 are screwed onto the end portions of the shafts 12 against the collars 27, thus maintaining the parts of the ball bearing assemblies at the lower ends of the hangers 11 in place on the end portions of the shafts 12. The shoulders 29 may be the end walls of tubular spacer members or distance pieces on the shafts 12 and such spacer members may comprise short lengths of pipe 31 on each shaft 12 and connected at their inner ends by a pipe union or coupling 32, the shoulders 29 then being the opposite end walls of the respective lengths of pipe 31 on each shaft 12.

The swingable structure of the device also includes a carrying or riding frame which comprises a pair of longitudinally extending members 33 which extend in adjacent parallel relation with each other for the greater part of their length and have supporting end portions 34 which are turned downward and slightly toward the ends of the stationary frame structure of the device and are provided at their lower ends with horizontal attaching members 35 which are secured on the tubular sections 31 of the spacing members on the shafts 12. The supporting portions 34 at corresponding ends of the members 33 also diverge slightly from each other toward their lower ends and the members 35 at the lower ends of the members 33 at the same end of the riding frame are secured on the respective sections 31 of the spacing member on the corresponding shaft 12. The members 34-33-34 may be lengths of pipe and the members 35 may be suitable pipe fittings such as T's, attached to the lower ends of the parts 34. The end portions 34 of each member 33 are stayed to each other by longitudinal connecting

bars 36 which may be lengths of pipe and which in turn are stayed to each other intermediate their ends by a cross stay bar 37 the members 33 also are stayed to each other intermediate their length by a cross stay 70 bar 38 which in turn is connected with the lower cross stay bar 37 by a vertical stay rod 39. The members 33 are additionally stayed to each other by cross stay bars 40 which also serve to support the shanks 41 75 of seats 42 which preferably are of the type that ordinarily is used on a bicycle. The members 33 are additionally stayed to each other by cross bars 43 which also support the shanks 44 of handle bars 45 which also 80 preferably are of the type that usually is provided on a bicycle. One or more of the seats 42 may be provided and a handle bar 45 preferably is provided for each of the seats 42. Also, a substantially U-shaped 85 stirrup member 46 is provided for use by the user of each of the seats 42, each stirrup member 46 having a pair of arms 47 pivotally attached at their upper ends, as at 48 to the members 33 and the arms 47 90 of each of the stirrup members may be stayed to each other by a cross rod 49.

From the foregoing description of the various parts of the device, the operation thereof may be readily understood. The 95 user or users of the device may impart an oscillatory motion to the riding frame by bodily rocking motion of his body or their bodies and since the hanger members 11 are supported anti-frictionally at their upper 100 ends, and the riding frame is supported anti-frictionally on the hanger members 11, it will be manifest that but slight effort is required to effect a desirable oscillatory movement of the riding frame. The riding 105 frame is of less length than the side members 1 of the stationary supporting frame and the hangers 11 at opposite ends of the stationary supporting frame structure therefore will be inclined downwardly and longitudinally of the device when the riding frame is in a position of rest as shown in Figure 1 and by the full lines in Figure 2. It therefore will be impossible for the riding frame to be oscillated to an extent sufficient 110 to cause complete revolution of the hangers about the shafts 13 and moreover the oscillation of the riding frame would be accompanied by an endwise rocking movement 115 of the riding frame, thus adding to the 120 pleasure of the users of the device. The stationary supporting frame is of considerably greater length and width than the length and width of the riding frame and therefore the device cannot be overturned 125 in use and the device thus is perfectly safe for use by children. As will be understood from the foregoing description and from the drawings, the device may be made principally of lengths of pipe and pipe fittings. 130

The length and dimensions of the component parts of the device may be varied according to particular requirements of the service for which a particular embodiment 5 of the invention is intended. For example, the length of the supporting frame and the riding frame of the device will be less when the device is intended for use by only one person than the length of the corresponding 10 parts of a similar device intended for the use of a plurality of persons at the same time.

Obviously, the invention is susceptible of embodiment in forms other than that which is illustrated in the accompanying drawings, and I therefore consider as my own all such modifications and adaptations thereof as fairly fall within the scope of the appended 15 claims.

20 I claim:—

1. In a swing, a supporting structure comprising a substantially rectangular base frame, standards on the corner portions of said base frame, axially aligned horizontal shafts on the upper end portions of the standards at each of the opposite ends of said base frame, pairs of hangers anti-frictionally supported at their upper ends on said shafts, transverse shafts carried by the 25 lower end portions of said pairs of hangers, a riding frame comprising a pair of longitudinally extending members having end portions turned downwardly and oppositely from each other, said end portions having attaching members at their lower ends for supporting said riding frame members on said last named shafts, longitudinal stay bars connecting the end portions of each 30 of said riding frame members, transverse stay members connecting the respective riding frame members, seats supported on certain of said transverse stay members, handle bars supported on other of said transverse stay members, substantially U-shaped stirrup members depending from said riding frame members, a transverse stay member between said longitudinal stay bars, and a vertical stay rod connecting said last named 35 transverse stay member with one of said 40 transverse stay bars on said riding frame members.

2. In a swing, a carrying frame comprising

ing a pair of adjacent parallel longitudinal members having supporting end portions turned downwardly and outwardly and diverging laterally toward their lower ends, 55 transverse members connecting the lower ends of said supporting end portions and including laterally extending alined journal portions, longitudinal stay members connecting the downturned supporting end portions of said frame members, and transverse stay members connecting said longitudinal members, certain of said transverse stay members being adapted to support handle bars 60 and other transverse stay members being adapted to support seats in adjacent relation with the handle bars.

3. In a swing, a carrying frame comprising a pair of adjacent parallel longitudinal members having supporting end portions turned downwardly and outwardly and diverging laterally toward their lower ends, 70 transverse members connecting the lower ends of said supporting end portions and including laterally extending alined journal portions, longitudinal stay members connecting the downturned supporting end portions of said frame members, and transverse stay members connecting said longitudinal members, certain of said transverse stay members being adapted to support handle bars 75 and other transverse stay members being adapted to support seats in adjacent relation with the handle bars, a transverse stay member between the middle portions of said longitudinal stay members, and a substantially vertical brace between said last named transverse stay member and one 80 of said first named transverse stay members. 90

4. In a swing, a carrying frame comprising a pair of adjacent parallel longitudinal members having supporting end portions turned downwardly, transverse members connecting the lower ends of said supporting end portions and including laterally extending alined journal portions, transverse stay members connecting said longitudinal members, certain of said transverse stay members being adapted to support handle bars 95 and other transverse stay members being adapted to support seats in adjacent relation with the handle bars. 100
